UNITED STATES PATENT OFFICE.

WILLIAM F. GILES, OF CHESTER, PENNSYLVANIA.

MOLD.

SPECIFICATION forming part of Letters Patent No. 658,007, dated September 18, 1900.

Application filed November 13, 1899. Serial No. 736,751. (No model.)

To all whom it may concern:

Be it known that I, WILLIAM F. GILES, a citizen of the United States, residing at Chester, in the county of Delaware and State of Pennsylvania, have invented a certain new and useful Mold, of which the following is a specification.

One object of my invention is to provide for satisfactorily drying sulfate of lime and other plastic material which is when manufactured frequently used as filling in the manufacture of paper and of cotton goods and silks.

To this and other ends my invention comprises the mold or carrier hereinafter described and claimed.

The nature, characteristic features, and scope of the invention will be more fully understood from the following description, taken in connection with the accompanying drawings, forming part hereof, and in which—

Figure 1 is a perspective view illustrating a mold or carrier embodying features of my invention. Fig. 2 is a horizontal sectional view of the same. Fig. 3 is a view principally in vertical section and illustrating upon a reduced scale the parts of the mold or carrier detached and opened.

In the drawings the mold is provided with pockets, as 1, of which four are shown, although that number may be increased or diminished.

The outer walls or frame 2 3 4 5 of the mold are provided with flanges 6, of wood or metal, which extend on both faces toward the center and form a recess 7 of any required depth on the inside of the mold.

8 and 9 indicate partitions which range in different directions to form the pockets, and there may be as many partitions as required to form the desired number of pockets.

The pieces 3 and 5 of the frame are shown as hinged to the part 2, and the part 4 is detachably secured, as by means of pins, so that these pins may be withdrawn, the part 4 detached, and the partitions removed. The partitions may be connected together, as indicated in Fig. 3, and the flanges 6 serve to retain them in place in the mold.

In use the material when comparatively 50 fluid is poured in the pockets 1, while the device lies upon its side. The material very rapidly becomes coherent and plastic and the device is then turned up on edge. In this position the flanges serve to retain the material 55 even though it shrinks in drying, and inasmuch as the device is open on both sides the material is exposed to the air freely, and consequently dries thoroughly and well, the device serving to support it while drying. When 60 the material is dry, it may be removed in coherent pieces by taking the described device apart. Subsequently the material when immersed in water quickly forms an emulsion which is useful in the arts. 65

It will be obvious to those skilled in the art to which the invention appertains that modifications may be made in detail without departing from the spirit thereof. Hence I do not limit myself to the precise construction 70 and arrangement of parts hereinabove set forth and illustrated in the accompanying drawings; but,

Having thus described the nature and objects of my invention, what I claim as new, 75 and desire to secure by Letters Patent, is—

1. A mold or carrier comprising a marginal recessed, pocketed frame.

2. A mold or carrier comprising a frame consisting of a number of marginal pieces and 80 provided on each side with inwardly-extending marginal flanges in combination with partitions adapted to the flanges, substantially as described.

3. A mold or carrier comprising recessed 85 marginal pieces hinged together and detachably connected, and partitions connected together and as a whole detachably fitted to said mold or carrier, substantially as described.

In testimony whereof I have hereunto 90 signed my name.

WILLIAM F. GILES.
